Invention:
Fred S. Carr,
By Emery Booth, James V. Varnay
Hilys.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed June 25, 1919. Serial No. 306,581.

To all whom it may concern:

Be it known that I, FRED S. CARR, a citizen of the United States, and a resident of Newton, in the county of Middlesex, Commonwealth of Massachusetts (whose post-office address is care of Carr Fastener Company, Cambridge, Massachusetts), have invented an Improvement in Fasteners, of which the following description, in connection with the accompanying drawings, is a specification, like characters on the drawings representing like parts.

This invention pertains to improvements in fasteners.

15 In the drawings, which show a preferred embodiment of a few forms of my invention:—

Fig. 1 shows a preferred form of my invention applied to two pieces of fabric to be held together, such, for instance, as the opposite sides of an oilskin coat;

Fig. 2 is a section on the line 2—2 of Fig. 1;

Fig. 3 is the same as Fig. 1 with a preferred additional feature, hereinafter more fully described;

Fig. 4 is a section on the line 4—4 of Fig. 3;

Fig. 5 shows a preferred form of fastener having the fastener elements opposite one another and concealed beneath the outer layer of fabric;

Fig. 6 is a section on the line 6—6 of Fig. 5;

Fig. 7 shows a modification of the fastener shown in Fig. 1; and

Fig. 8 is a section on the line 8—8 of Fig. 7.

Referring to Fig. 1 of the drawings, I have shown an outer layer of fabric 9 carrying a stud element 10 secured thereto in any suitable way and a cooperating socket element 11 secured to fabric 12, the marginal portion of which is illustrated as underlying the fabric 9. Where, as shown in Fig. 1, both stud and socket are exposed, the stud is preferably provided with an elongated neck 13, preferably offset as best shown in Fig. 2, and turned inwardly at the end, being provided with a head 14. The socket 11 is provided with a stud-receiving aperture, herein shown as a slot provided by upwardly projecting portions 15 providing a channel into which the head 14 of the stud may be entered from the top by a movement

in a general direction parallel to the adjacent marginal portions of the fabric 9 and 12. The front of the channel is preferably slotted as shown, to permit passage therethrough of that portion of the neck 13 adjacent the head 14. Accidental separation of stud and socket is preferably opposed by resilient means, herein typified by the spring portion 16, which may be struck up from the metal forming the socket 11.

When it is desired to connect the stud and socket, the stud may be entered in the socket by movement thereof into the channel, such movement being in a direction generally parallel with the adjacent marginal portions of the fabric 9 and 12. When under strain tending to pull the fabric portions 9 and 12 in opposite directions in a general direction perpendicular to the marginal portions thereof, the neck of the stud adjacent the head engages the side of the aperture adjacent the material carrying the stud, thereby providing an unyielding abutment opposing accidental separation of the fastener. When it is desired to separate the stud and socket, the former is moved downwardly or the latter moved upwardly when a preferred arrangement shown in the drawings is utilized.

Fig. 3 differs from Fig. 1 in that a notch 17 is provided into which the neck of the stud enters when under lateral strain, this notch preferably being relatively shallow so that to effect separating movement it is not necessary to exert separating strain in more than one general direction.

In the form of my invention shown in Fig. 5, the stud and socket are both concealed beneath the outer layer of material, being opposite one another, but otherwise cooperating in the same way as previously described in connection with Fig. 1 and Fig. 3.

In Fig. 7, I have shown a form of stud and socket differing somewhat from that shown in the other figures in that the stud-receiving channel is not slotted, but is made in the form of a pocket into which the stud is adapted to drop. In this form of the invention, the neck of the stud may be offset in a plane generally parallel with the adjacent surfaces of the fabric, thereby to lie somewhat flatter than in the other illustrative embodiments of my invention, the stud preferably having the general forma-

tion of a hook. In Fig. 7 I have shown a spring 18 for holding the head of the stud entered in the pocket, the spring preferably being, as shown, separate from the material forming the body of the socket.

While I have shown and described a few preferred embodiments of my invention, it will be understood that a considerable number of changes involving omission, substitution, alteration and reversal of parts, and even changes in the mode of operation, may be made without departing from the scope of my invention, which is best defined in the following claims:

- 10 15 1. A separable fastener comprising, in combination, cooperating stud and socket members, the stud member having a shank projecting laterally past the edge of the stud-carrying fabric and the socket member having a stud-receiving channel disposed at an angle to the normal line of strain between the fabrics, said socket secured to the socket-carrying fabric at a point beyond the edge of the stud-carrying fabric when stud and socket are engaged one with the other.
- 20 25 2. A fastener comprising, in combination, a stud and a socket, said socket having a stud-receiving channel disposed in a general direction perpendicular to the line of strain between stud and socket, said channel hav-

ing a relatively slight indentation extending in the direction of the line of strain into which the stud is pulled when under strain, said indentation proportioned to permit lateral movement of the stud into semi-locked 35 relation to the socket, while permitting separation of stud and socket by a resolution of force in a direction lengthwise of the channel and toward the entrance opening thereof.

3. A stud and socket fastener comprising, 40 in combination, a stud having a relatively long neck or shank portion and a head, a socket providing a channel for receiving said head of said stud, said shank or neck being offset and having said head projecting inwardly therefrom to permit entrance of said head into said channel.

4. A stud and socket fastener comprising in combination, a stud having a relatively long neck or shank portion and a head, a 50 socket providing a channel for receiving said head of said stud, said channel extending in a direction transverse to the line of strain between the stud and socket, and said shank or neck being offset to permit entrance of 55 said head in said channel.

In testimony whereof, I have signed my name to this specification.

FRED S. CARR.
